UNITED STATES PATENT OFFICE.

SAMUEL HEATH, OF PHILADELPHIA, PENNSYLVANIA.

VAPOR-BURNER.

1,016,497.

Specification of Letters Patent.

Patented Feb. 6, 1912.

Application filed November 9, 1910. Serial No. 591,426.

To all whom it may concern:

Be it known that I, SAMUEL HEATH, a citizen of the United States, residing at Philadelphia, in the county of Philadelphia and State of Pennsylvania, have invented 5 a certain new and useful Improvement in Vapor-Burners, of which the following is a specification.

My invention relates to a new and useful 10 improvement in vapor burners, and has for its object to construct a burner which will produce a gas from a combination of oils, the base of which is kerosene, and to burn this gas to produce an enormous heat within 15 out smoke or odor.

With these ends in view, this invention consists in the details of construction and combination of elements hereinafter set forth and then specifically designated by 20 the claims.

In order that those skilled in the art to which this invention appertains may understand how to make and use the same, I will describe its construction in detail, referring by letter to the accompanying drawing forming a part of this specification, in which—

Figure 1, is a vertical sectional view of 30 my improved vapor burner, showing the vaporizer, tank and other connections in elevation. Fig. 2, a segmental plan of the vapor burner, portions being broken away to clearly illustrate the construction, and Fig. 3, an enlarged vertical sectional view 35 of the vaporizer, showing means for regulating the spindle from the side. Fig. 4, is a plan view of the open work plate.

In carrying out my invention as here embodied, A represents the body of the vapor 40 burner which may be supported by a stand, or if preferred may be supported within the ordinary coal stove in either the heating or cooking style of stove. Said body comprises two perforated casings and one im- 45 perforated casing, forming combustion and air chambers, held together in a suitable manner as will hereinafter be described.

B denotes a perforated casing which is 50 permanently closed at the top by the lid C which may be formed integral with the casing or may be made separate and secured in place in some suitable manner. In this casing are mounted two partitions D and E, each of which has a central opening F; 55 the partition E being mounted in proximity to the lower end. About this casing is

placed a second perforated casing G, the two being held together by suitable bolt rods or their equivalent H, which pass through the casings. About the casing B 60 is placed a ring I having an external flange J said flange lying against the outer surface of the casing G, thus spacing the casings B and G, in this way keeping a combustion chamber K the same size throughout its 65 entire length. This ring I is imperforated thus closing the lower end of the combustion chamber K. On the top of the casing G is mounted an open work ring L which encircles the casing B, the upper end of said 70 casing extending a short distance above said ring. The lower end of the casing B rests upon an open work plate M having a downwardly extending flange O. Through this plate pass a number of rods P, headed as 75 at Q, the upper ends passing through the ring L and having nuts R mounted thereon, thus holding the parts in place.

Outside of the perforated casing, covering rings and plates is an imperforated cas- 80 ing S, both ends being open, the lower end resting upon the open work plate M. On top of the perforated casing B is mounted damper plate T, having a nipple U threaded into the lid C. On top of this plate T is 85 mounted the damper V which rotates about the screw W threaded in the nipple U. This permits the heat to be deflected downward when the damper is closed and when the damper is open the heat will pass through 90 the plate T for heating a utensil which may rest upon the damper.

X shows a cross-coupling to which is connected a pipe Y leading from the supply pipe Z, having a shut-off cock A' therein, 95 said supply pipe leading from the tank or reservoir B' adapted to hold the fuel. Into the coupling X at right angles to the pipe Y is threaded the vaporizer C' having an external thread D' throughout a portion of 100 its length from the upper end thereof. The upper portion of the vaporizer is closed by a plug E', having a vertical opening F', the lower end of said opening being conical in shape to form a valve seat G', with which 105 engages the needle valve H' formed with the spindle I', said spindle having a longitudinal groove J' of sufficient length to extend beyond both ends of the partition K', through which is threaded the spindle I'. 110 This partition may be held in place by a screw L' which passes through the vaporizer

or in some other suitable manner, to form the generating chamber M'. The spindle I' passes out of the coupling at a point directly opposite to where the vaporizer is 5 mounted, and this end is packed with a stuffing box N'.

On the end of the spindle may be mounted the hand wheel O' so that the spindle may be turned from the bottom, or said spindle 10 may be provided with a double knuckle joint P' which is also connected with the short shaft Q' journaled in the bracket R' and having mounted thereon a hand wheel S', this construction permitting the spindle to 15 be rotated from the side.

The opening leading from the coupling at a point opposite to where the pipe Y enters may be closed by a plug T' if only one 20 burner is being used, or a pipe may be threaded in the coupling at this point so as to connect any number of burners to the one supply pipe. On the upper end of the vaporizer C' is mounted an open work frame U' having a central boss or hub V' which is 25 slightly raised from the body or ring of the frame, and on this frame rests the flange O of the plate M, thus holding the body of the burner in an upright position in relation to the vaporizer. On the vaporizer is also 30 threaded a cup W' and when in place it rests upon the boss V' and is adapted to hold a few drops of oil for heating the vaporizer to begin the generation of gas from the fuel.

In practice a few drops of oil are placed 35 in the cup W', the needle valve H' brought into engagement with its seat G' so that the outlet F' is closed; the valve cock A' is then opened to permit the fuel to flow from the reservoir B'. The heat produced from the 40 burning oil in the cup W' will heat the vaporizer causing the oil in the generating chamber N' to rise in temperature and form a gaseous substance which, when the valve is opened in the vaporizer, will flow into the 45 chamber within the casing B, at which point it may be lighted. From here it will pass through the perforations to the combustion chamber K, where it will combine with the air going in at the bottom between the perforated casing G and the imperforated casing S, passing through the casing G into the 50 combustion chamber; it being understood that a certain amount of air has first been drawn into the casing B and mixed with the 55 gas during its upward flow within the casing B.

The construction as here described so 60 thoroughly mixes the gas and air that all substances therein are burned, leaving no residue and being practically odorless.

The oil most suitable for use is a combination of kerosene oil, alcohol and camphor. Because of the great amount of hydrogen and carbon in each ingredient when mixed, 65 they produce a compound which is highly

inflammable and which may be readily changed to gas by heating, and when burned will eliminate practically all odor and residue which would produce a smoke.

The elements of the combination will not 70 thoroughly mix until they commence flowing from the receptacle or reservoir at which time the gravitation causes each to combine in the ratio named below and this ratio remains the same during the continuance of 75 the flow from the reservoir, and when burned will produce an intensely hot blue flame until the last drop is used.

The mixture comprises approximately 89% kerosene, about 9% alcohol, the remainder 80 or nearly 2% being camphor. This same mixture may be utilized in oil or gas engines and when the combustion takes place will leave no odor or residue the same as when burned in a stove, and the strength of 85 the explosion is as great as the explosion produced by the use of gasoline. This mixture when used for operating engines is considerably cheaper than gasoline since the element of greatest quantity is illuminating 90 oil or kerosene, which can be bought at a reasonable figure.

Of course I do not wish to be limited to the exact details of construction here shown, as these may be varied within the limits of 95 the appended claims without departing from the spirit of my invention.

Having thus fully described my invention, what I claim as new and useful, is—

1. In a vapor burner the combination of a 100 perforated casing closed at the top, a second perforated casing surrounding the former, means for fastening them together, an open work ring surrounding the first named casing and resting upon the last named casing, 105 an imperforated ring having an external flange resting against the lower end of the surrounding casing and surrounding the inner casing, an open work plate having a downwardly extending flange, means for holding the open work plate and the open work ring in position, an imperforated casing surrounding the first named casings and resting upon the open work plate, a damper plate mounted upon the inner perforated 110 casing, a damper pivoted upon said damper plate, a vaporizer, and means for attaching the body of the burner thereto.

2. In a vapor burner a combination of a 120 perforated casing closed at the top, a second perforated casing surrounding the former, means for fastening them together, an open work ring surrounding the first named casing and resting upon the last named casing, 125 an imperforated ring having an external flange resting against the lower end of the surrounding casing and surrounding the inner casing, an open work plate having a downwardly extending flange, means for holding the open work plate and the open

work ring in position, an imperforated casing surrounding the first named casings and resting upon the open work plate, a damper plate mounted upon the inner perforated casing, a damper pivoted upon said damper plate, a vaporizer, an open work frame having a hub formed therewith, said hub being in a plane above the frame, said hub being threaded upon the vaporizer and means for 10 holding a combustible liquid whereby the vaporizer may be heated.

3. In a vapor burner a combination of a perforated casing closed at the top, a second perforated casing surrounding the former, 15 means for fastening them together, an open work ring surrounding the first named casing and resting upon the last named casing, an imperforated ring having an external flange resting against the lower end of the 20 surrounding casing and surrounding the inner casing, an open work plate having a downwardly extending flange, means for

holding the open work plate and the open work ring in position, an imperforated casing surrounding the first named casings and 25 resting upon the open work plate, a damper plate mounted upon the inner perforated casing, a damper pivoted upon said damper plate, a vaporizer, an open work frame having a hub formed therewith, said hub being 30 in a plane above the frame, said hub being threaded upon the vaporizer, a cup threaded upon the vaporizer and resting upon the hub of the frame for holding a combustible liquid whereby the upper end of the vaporizer 35 may be heated, and means for supplying the vaporizer with fuel.

In testimony whereof, I have hereunto affixed my signature in the presence of two subscribing witnesses.

SAMUEL HEATH.
